KEY RING CONSTRUCTION

Gustav A. Loercher, Greenwood, R. I., assignor to
Carl-Art, Inc., a corporation of Rhode Island

Application January 20, 1938, Serial No. 185,873

8 Claims. (Cl. 70—459)

My present invention relates to the jewelry art, and has particular reference to a novel construction of key rings.

It is the principal object of my invention to provide a key ring which will accommodate a large number of keys, and which locks the keys against accidental or inadvertent removal.

It is a further object of my invention to provide a novel key ring which is readily opened to permit the insertion or removal of a key or keys, and is readily closed without exertion of substantial pressure or force.

Another object of my invention is to provide a construction having a small number of readily manufactured parts, easily assembled together, whereby the cost of manufacture is reduced.

With the above and other objects and advantageous features in view, my invention consists of a novel arrangement of parts more fully disclosed in the detailed description following, in conjunction with the accompanying drawing, and more specifically defined in the claims appended thereto.

In the drawing:

Fig. 1 is a plan view of a novel key ring;

Fig. 2 is a side elevation thereof;

Fig. 3 is a view similar to Fig. 1, showing the key ring in open position;

Fig. 4 is an enlarged perspective view similar to Fig. 3, showing the back of the key ring; and

Fig. 5 is an enlarged sectional detail on the line 5—5 of Fig. 2.

It has been found desirable to manufacture a key ring which may be easily locked to prevent accidental and inadvertent opening, and thus prevent loss of a key or keys, and which requires very little effort or force to close the key ring and to maintain the parts against accidental opening. To this end, I have designed a key ring having a swinging head, which may be swung so as to open a passageway for the insertion or removal of a key or keys, the head having a lock device pivoted thereto which may be swung with very slight effort, and which securely locks the parts when in closed position, against accidental opening.

Referring to the drawing, the novel key ring 11 includes an open ring 11 to one end of which a head 12 is hingedly secured by means of a rivet 13, the ring 11 being preferably of spring material, and the head 12 being preferably of stamped sheet metal. As is clearly disclosed in Fig. 4, the free end of the ring 11 is milled or shaped to provide a depressed portion 14 and an upstanding tooth 15, and the head 12, within which the free

ring end is removably received, has a slotted portion 16 spaced from the free head end to provide an overhang tip 17, so as to accommodate the tooth 15 and the depressed portion 14 of the ring end. The head portion 12 may therefore be moved over so as to permit relatively free engagement and nesting of the ring end therein, as shown in Fig. 5, with the tooth portion 15 positioned in the slotted portion 16 and the recess 14 positioned underneath the tip 17 of the head. In this position, the parts are in engaged relation, but can be readily separated by pressing inwardly on the ring and then lifting the head portion 12.

The lower side of the free end of the ring 11 has a notch 18 formed therein, and an arm 19 is pivotally secured to the head 11, as by means of a rivet 20, the arm 19 having a tooth end 21, and a movably engageable finger piece 22, whereby the arm 19 may be manually moved so as to snap the end 21 past the edge 23 of the notch 18, the head having a slot 24 in one side thereof to permit the necessary inward movement of the finger 22. When the tooth 21 is so positioned, see Fig. 5, it does not securely lock within the notch 18, but may be readily swung outwardly to disengage therefrom; since the arm 19 is retained in the position shown in Fig. 5 because a slight effort is necessary to bring the end of the tooth 21 past the edge 23, the head 12 cannot be swung away or detached from the free end of the ring 11, because such separation requires a slight inward movement of the free ring end so as to bring the tooth 15 below the end 17, which movement is effectively prevented by engagement of the notch 18 with the tooth 21.

Aligned openings 24a are provided in the sides of the head 12 to provide a passageway for receiving the snap hook of a key chain, and the hinged end of the ring 11 is notched as indicated at 25 to abut against the end 26 of the head thus providing a limiting stop for the separating swinging movement of the parts.

While I have described the novel arrangement of the parts as specific to a key ring construction, the same or similar arrangement of parts may be applied to a padlock arrangement for general use, as the invention is applicable to any type of keyless padlock, and may obviously be used in connection with a hasp and staple such as is used for a gate, a trunk or the like to provide an easily applied and easily removed padlock device. Desired changes in the shape of the parts, in the materials used, in the relative arrangement of the parts, and in their ornamentation, may be made to suit the requirements for

different designs of key rings and for keyless locks, without departing from the spirit and the scope of the invention as defined in the appended claims.

5. I claim:

1. In an article of the type described, a ring member of resilient material, a head having an end wall member and hinged to said ring member at one end thereof, cooperating detachably engageable parts on the free end of said ring member and said head member comprising a tooth and a detent on one member and a cooperating detent and tooth on the other member, and additional means for releasably locking said parts in engaged relation.

10. 2. In an article of the type described, a ring member of resilient material, a head having an end wall member and of channel shape having an end wall and two sides and hinged to said ring member at one end thereof, cooperating detachably engageable parts on the free end of said ring member and said head member comprising a tooth and a detent on one member and a cooperating detent and tooth on the other member, and a movable element on said head member removably contacting said ring member for releasably locking said parts in engaged relation.

15. 3. In an article of the type described, a ring member of resilient material, a head member hinged to said ring member at one end thereof, cooperating detachably engageable parts on the free end of said ring member and the end wall of said head member, comprising a tooth on the ring end and a recess on the head, and a movable element on said head member removably contacting said ring member for releasably locking said parts in engaged relation.

20. 4. In an article of the type described, a ring member of resilient material, a head member hinged to said ring member at one end thereof, cooperating detachably engageable parts on the free end of said ring member and said head member, said ring member having a notch, and a manually movable arm hinged to said head member and having a tooth engageable with said notch, said ring member being movable outwardly against its spring tension to permit engagement of said arm tooth with said notch, and springing back to releasably lock said arm tooth in said notch.

25. 5. In an article of the type described, a ring member of resilient material, a head member hinged to said ring member at one end thereof,

cooperating detachably engageable parts on the free end of said ring member and said head member, comprising a tooth on one member and a detent on the other member, said ring member having a notch, and a manually movable arm hinged to said head member and having a tooth engageable with said notch, said ring member being movable outwardly against its spring tension to permit engagement of said arm tooth with said notch, and springing back to releasably lock 10 said arm tooth in said notch.

30. 6. In an article of the type described, a ring member of resilient material, a head member hinged to said ring member at one end thereof, cooperating detachably engageable parts on the free end of said ring member and said head member, comprising a tooth on the ring end and a recess on the head, said ring member having a notch, and a manually movable arm hinged to said head member and having a tooth engageable with said notch, said ring member being movable outwardly against its spring tension to permit engagement of said arm tooth with said notch, and springing back to releasably lock 15 said arm tooth in said notch.

35. 7. In a key ring, a ring member of resilient material, a head member hinged to said ring member at one end thereof and having spaced sides to receive the free end of the ring member, said head member being slotted at its free end to provide a recess and an overhang tip, and said ring member having a tooth and a recess at its free end adapted to respectively releasably engage said head member recess and said overhang tip, said ring member having an inner groove, and said head member having an arm hinged thereto provided with a tooth engageable with said groove.

40. 8. In a key ring, a ring member of resilient material, a head member hinged to said ring member at one end thereof and having spaced sides to receive the free end of the ring member, said head member being slotted at its free end to provide a recess and an overhang tip, and said ring member having a tooth and a recess at its free end adapted to respectively releasably engage said head member recess and said overhang tip, said ring member having an inner groove, and said head member having an arm hinged thereto provided with a tooth engageable with said groove, said arm having a manually engageable finger and said head member having a slot to receive said finger.

GUSTAV A. LOERCHER.
